UNITED STATES PATENT OFFICE

WILLIAM M. GRIFFIN, OF FORT WAYNE, INDIANA, ASSIGNOR TO THE WAYNE HOME EQUIPMENT COMPANY, OF BALTIMORE, MARYLAND, A CORPORATION OF MARYLAND

COMBUSTION TUBE FOR OIL BURNERS

Application filed September 24, 1928. Serial No. 308,012.

My invention relates to apparatus for burning liquid fuel, and particularly to the combustion tubes of such apparatus. The invention may be used on oil burners of relatively small size, such as those for heating dwelling houses and for larger installations.

To ensure safe and efficient combustion of the fuel, the rearward part of the flame must be maintained a short distance in front of the burner nozzle. If the flame rests upon or surrounds the end of the nozzle, carbon deposits will soon partially or wholly close the fuel outlet orifice, or accumulate on the nozzle so as to prevent normal discharge of air from the combustion tube, or interfere with ignition, or all of these. If the flame is maintained too far forward of the end of the nozzle, it is apt to be blown out; whereupon normal continued feed of fuel upon the heated firebox wall is liable to cause an explosion.

This invention constitutes an improvement on the invention of Harry F. Sennen, application for Patent Serial No. 307,988, filed September 24, 1928.

While an ample quantity of air must be provided I have found that it is very important that the air supplied to the combustion tube should be so directed that it will not pass directly over the flame.

The principal object of my invention is to so direct the air entering the combustion tube that it will not flow directly over the spray nozzle. In fact I prefer that it be deflected backwardly, that is, away from the front end of the combustion tube upon entering said tube. A device so constructed produces safe and efficient combustion regardless of the exact position of the spray nozzle with relation to the inner end of the combustion tube and therefore but slight care need be used in assembling the oil tube and nozzle in the combustion tube.

A rotating air supply fed thru the wall of the combustion tube, toward the back end thereof maintains a rapidly rotating tubular air column, constantly emerging from the front of the combustion tube, with substantially no air pressure at the center where the spray nozzle is located.

Two embodiments of my invention are ill-

ustrated in the accompanying drawings, in which:—

Figure 1, is a perspective from above the combustion tube with the burner assembled therein, comprising a main tube and branch tubes connected with the main tube tangentially, one to the top side and the other to the bottom side, the back end of the tubes being broken away, 55

Fig. 2, is a cross section of the tubes only, 60 on the line 2—2 of Fig. 1, and

Fig. 3 is a longitudinal section of the tubes only, on the line 3—3 of Fig. 2,

Fig. 4 is a top plan view of another form of the combustion tube and burner assembly 65 with the rearward ends of the connections broken away. The combustion tube proper and air supply tube are two parallel tubes formed integrally and tangentially connected, 70

Fig. 5 is an end view of the combined combustion and air supply tube from the rear,

Fig. 6 is a cross section of the combined combustion and air supply tube only on the line 6—6 of Fig. 4, 75

Fig. 7 is a longitudinal section of the combined combustion and air supply tube only on the line 7—7 of Fig. 5,

Fig. 8 is a longitudinal section on the line 8—8 of Fig. 5. 80

Referring now to the drawings and particularly to Figs. 1 to 3 inclusive; 1 is the main combustion tube, with branch tube 2, closed at its front end, connected with the main tube tangentially on the under side of the main tube, and branch tube 3, also closed at its front end, connected with the main tube tangentially on the top of the main tube, so that air forced into tubes 2 and 3 from their rearward ends will rotate within the main tube 1, around the burner nozzle 5 as indicated by the arrows. Electrodes 6, 6^a are conveniently located to supply initial ignition.

Obviously the branch tubes need not be connected to the main combustion tube directly 95 opposite each other, and if one was so connected behind the other, two currents of air would be created in the main tube both rotating in the same direction. More than two branch tubes, connected one behind the other might be 100

used if more than two air currents were desired.

The preferred form of the device is shown in Figs. 4 to 8 inclusive, and will now be described. The main combustion tube 14 has a parallel air supply tube 15 closed at its front end, both tubes preferably formed of one casting with a tangential opening from the latter to the former at 16. This opening may be 10 coextensive with their joint length or a less distance. In the drawings it has been shown as extending from a partition 17 to the front end of the air supply tube 15 with a cross partition 18 of suitable height to prevent all the 15 air supplied to the tube 15 from the rear 19 impinging upon the front end 20 of said tube, but will divert part of the air to the main tube 14 in a separate current. Obviously there might be a plurality of such partitions 20 18 and of different heights if desired, if more than two such streams of air into the main tube from the air supply tube are desired. Partitions 17, 18 and 28 are all inclined backwardly, that is so as to divert the air entering 25 the combustion tube 14 toward the back of said tube.

An axially adjustable housing 21 completely closes the back end of the main tube 14. Through this housing extend the electrodes 30 6 and 6' and the fuel oil supply tube 22, the inner end of which terminates in the spray nozzle 5.

An opening through the side of the main tube, is closed by a mica window 23 and is protected externally by a window housing 24, having a hinged guard door 25, which may be raised to observe the conditions on the inside of the fire-pot (not shown).

The combined main tube and air supply 40 tube may have a longitudinal passage 26 to supply air direct from outside the fire-pot to its interior and the supply of direct air therethrough is regulated by the adjustment of the position of the cover plate 27.

Although certain forms of the invention 45 have been shown and described, it will be understood that a mechanic, working within the scope of what is claimed, may make changes, without departing from the spirit 50 of the invention.

I claim as my invention and desire to secure by Letters Patent of the United States:—

1. In a combustion tube for apparatus for burning liquid fuel, means for supplying air 55 through the wall of said tube substantially tangentially thereof and means for diverting the air so supplied toward the back end of the combustion tube.

2. In a combustion tube for apparatus for 60 burning liquid fuel, a fuel supply pipe and its spray nozzle positioned substantially axially of said tube, means for supplying air through the wall of said tube substantially tangentially thereof and contiguous to said 65 nozzle and means for diverting the air so sup-

plied toward the back end of the combustion tube.

3. In a combustion tube for apparatus for burning liquid fuel, a fuel supply pipe and its spray nozzle positioned substantially axially of said tube, means for supplying air through the wall of said tube substantially tangentially thereof and contiguous to said nozzle, means for dividing the air current so supplied and means for diverting the air so supplied 70 toward the back end of the combustion tube. 75

4. A combustion tube for apparatus for burning liquid fuel, and an air supply tube closed at the front end substantially parallel with the combustion tube and connected therewith substantially tangentially of said combustion tube, and internal partitions sloping backwardly to cause the air entering the combustion tube from the air supply tube to flow toward the back of said combustion tube. 80 85

In testimony whereof I have hereunto set my hand.

WILLIAM M. GRIFFIN.
